UNITED STATES PATENT OFFICE

DONALD S. BARROWS, OF ROCHESTER, NEW YORK, ASSIGNOR, BY MESNE ASSIGNMENTS, TO SIMPLEX EQUIPMENT COMPANY, INC., OF NEW YORK, N. Y., A CORPORATION OF DELAWARE

OUTLET FOR GENERATOR LEADS

Application filed May 31, 1927. Serial No. 195,447.

The invention relates to generators, particularly such as form part of the equipment in car lighting systems and more particularly to the generator lead construction.

5 One of the objects of the invention, generally stated, is to provide a simple, practical and thoroughly dependable generator lead outlet which not only serves to enclose and protect the leads against bending or chafing 10 where they enter the housing but also is capable of performing other and more specific functions to be set forth.

An important object of the invention is to provide a lead outlet having means thereon 15 and cooperating therewith for maintaining the end cover in place.

In generators of the type disclosed there is usually provided a pole changer switch which is covered or enclosed by a dome or end cover 20 which serves to protect the parts and exclude dirt, water or other foreign matter. The outlet of the present invention is particularly well adapted for use upon or as part of a generator of this character inasmuch 25 as it may be and preferably is provided with a securing means for holding the end cover or dome against displacement.

Another object of the invention is to provide a lead outlet which is hinged or pivotally mounted with respect to the frame of the generator and held detachably in place in such manner that it may be swung out of the way or to non-obstructing position in case 30 access must be had to certain parts of the generator and associated mechanisms, such as the pole changer switch, its terminals, or the like, as may frequently occur in actual service.

40 A still further object of the invention is the provision of an outlet of this character so constructed as to have detachably connected therewith the usual canvas or other flexible hose or conduit which encloses and protects the leads.

An additional object of the invention is to provide a structure of this character which will be simple and inexpensive to manufacture, easy to install, positive in action, efficient 50 and durable in service, and well adapted to

meet the varying conditions of hard practical use.

To the attainment of the foregoing and other objects and advantages, the invention preferably consists in the details of construction 55 and the arrangement and combination of parts to be hereinafter more fully described and claimed, and illustrated in the accompanying drawing in which:

Figure 1 is a view of a generator with the 60 casing thereof in section, an embodiment of the invention being disclosed in applied or operative position, and

Figure 2 is an end elevation.

Referring more particularly to the drawing I have illustrated a more or less conventional type of generator designated generally by the reference character 1 and having secured thereto a bracket 2 as is the ordinary practice in car lighting installation. And as 70 conducive to a clearer understanding of certain features of this invention, it may at this point be noted that in car lighting systems the generator is oftentimes suspended from the car body or from the truck and is driven from a car axle. Accordingly, the direction of drive of the generator is subjected to reversals depending upon the direction in which the vehicle moves and where the generator has associated with it a storage battery to be 75 charged thereby, as is usually the case, it is important that the polarity of the output of the generator be appropriately controlled when its direction of drive changes in order 80 that the relation of the generator to the battery for charging will be consistently appropriate. Such control of the polarity of the generator is oftentimes achieved by what is termed broadly a "pole changer" and this may be in the form of a switch or in any other 85 suitable form and is adapted to be actuated in one direction or the other according to the direction in which the generator drive is commenced. This pole changer is usually and 90 preferably associated directly with the generator and is preferably incorporated therewith. The generator is represented as enclosed within or embodying a casing or housing 95 3 to which is secured a head 4 carrying a bracket 5 provided for the purpose of sup-

porting a pole changer of the character above-mentioned in connection with this particular type of apparatus. The structure also further includes an end cover or dome 6 cooperating with the head 4 for the purpose of constituting an end closure so that all the generator parts themselves will be protected against the ingress of water, dirt or other foreign matter, a feature of particular importance where the generator is exposed as when driven from a car axle.

In accordance with certain features of my invention, I provide an outlet device indicated generally at 7 and here shown as comprising an arm 8 of curved shape pivoted at one end, as represented at 9, upon an ear 10 formed upon or carried by the head 4. This arm has its other end detachably connected by a removable pin 11 or the like with one or more ears 12 on the bracket 5 so that upon removal of the pin, or its equivalent, the arm may be permitted to swing down to give access to the mechanism of the pole changer switch. The arm 8 may be of hollow construction or more or less channel shaped in cross section to form an enclosing guide for the generator leads 13 which are brought through an opening or open portion 14 in the upper side of the curved arm for connection with the terminals of the generator. Intermediate its ends the arm 8 is formed with a cylindrical outstanding portion 15 from which projects a reduced tubular extension 16 preferably inclined downwardly. The outstanding portion 15 is chambered out at 17 and communicates with the interior of the tubular extension 16 and the hollow arm 8, the leads 13 being brought out through the chamber 17 and tubular extension.

The dome 6 above described is centrally apertured so as to be slipped over the outstanding cylindrical portion or projection 15, a packing gasket 18 being interposed between the outer surface of the arm 8 and the inner face of the confronting portion of the dome or end cover. The dome is secured against displacement by means of a lever nut or the like 19 screwed upon the exteriorly threaded outstanding projection 15, the dome being thereby clamped firmly in place with respect to the arm and to the abutment shoulder 20 provided on the head 4.

I also provide a canvas or other flexible hose-like conduit 21 for the protection of the leads, and in accordance with certain features of my invention I provide a secure and dependable anchorage for the conduit 21 in that the latter is engaged upon the reduced extension 16 and secured with respect thereto as by means of any suitable clip or clamp 22 of ordinary pattern.

Considering now the action of the apparatus, it might first be noted that the nut 19 permits the end cover or dome 6 to be rigidly and securely clamped against the shoulder 20

of the generator frame or head, thus dependably enclosing the pole changing apparatus, the connections thereto, and other parts of the generator, and dependably protecting such parts as these against ingress of water or such foreign matter as might be thrown up from the roadbed. Also, the generator leads 13 are dependably held within the dome 6, as by the channeled member 8 not only in such a way as to prevent kinking or bending but also out of possible interference with such mechanism as the pole changer device, for example. Moreover, the leads are brought out of the dome and dependably held in a way that prevents kinking or bending while the downwardly directed tube-like extension 16 either independently or in co-action with the conduit 21 dependably prevents water or foreign matter from getting into the generator casing through the opening through which the leads are brought out.

Should it be desired to gain access to the interior of the housing as, for example, to inspect or repair such mechanism as the pole changer device, such access may be gained in a rapid and simple manner. The nut 19 is unscrewed from the threaded shoulder 15 and is allowed to slip down upon the tubular extension 16, whereupon the dome 6 itself may be moved in a direction toward the left, as viewed in Figure 1, and itself slid along the reduced extension 16 or along the conduit 21 for a sufficient distance to bring it into substantially non-obstructing relation to the generator. Also, the pin 11 may be withdrawn so that the curved arm 8 may be swung in counter-clockwise direction about its pivot 9, whence the dome 6, as well as the outgoing lead wires with the conduit 21, are similarly swung downwardly and completely out of the way. Thus, access to the generator parts including the pole changer is readily and easily gained, it being noted that even during the swinging of the arm 8 the leads 13 are dependably safeguarded against possible harm in that the leads 13 emerge from the arm 8 adjacent the pivot 9 so that they are themselves subjected to a minimum amount of bending.

The manner of reassembly of the parts will be clear in view of the foregoing, but it might be noted that the arm 8 is first swung upwardly about its pivot 9 and the pin 11 re-inserted to hold the arm securely to the ears 12 on the bracket 5; such action practically centralizes the threaded portion 15 with respect to the shoulder 20 of the generator frame or head and the parts are thus in readiness to receive the dome 6, whence the nut 19 may be driven home to clamp the dome 6 against the generator frame.

It will thus be seen that there has been provided in this invention a construction in which the several objects hereinabove noted, as well as many thoroughly practical advan-

8 tages are successfully achieved. It will be
9 seen that the apparatus is of simple but thor-
10oughly practical construction, is capable of
11 being embodied in inexpensive form, is easily
12 and quickly manipulated and, moreover, is
13 well adapted to meet the varying conditions
14 of hard practical use. It will furthermore
15 be seen that the leads are dependably housed
16 and protected and, moreover, in a manner that
17 insures protection of the leads even during
18 the assembly or disassembly of the parts.

19 As many possible embodiments may be
20 made of the above invention and as many
21 changes might be made in the embodiment
22 above set forth, it is to be understood that all
23 matter hereinbefore set forth or shown in
24 the accompanying drawing, is to be inter-
25 preted as illustrative and not in a limiting
sense.

26 Having thus described the invention, I
27 claim:

28 1. In a generator including a housing hav-
29 ing at one end a head carrying a bracket, and
30 a removable dome engaging the head, a lead
31 outlet pivotally connected with the head and
32 detachably connected with the bracket, the
33 major portion of said outlet being located
34 within the dome and a portion extending
35 through the dome.

36 2. In a generator including a housing hav-
37 ing at one end a head carrying a bracket, and
38 a removable dome engaging the head, a lead
39 outlet pivotally connected with the head and
40 detachably connected with the bracket,
41 the major portion of said outlet being locat-
42 ed within the dome and a portion extending
43 through the dome, and means on said project-
44 ing portion for securing the dome in place.

45 3. In a generator including a housing hav-
46 ing at one end a head carrying a bracket, and
47 a removable dome engaging the head, a lead
48 outlet pivotally connected with the head and
49 detachably connected with the bracket, the
50 major portion of said outlet being located
51 within the dome and a portion extending
52 through the dome, and means on said project-
53 ing portion for securing the dome in place,
54 said projecting portion terminating in a re-
55 duced tubular extension.

56 4. In a generator including a housing hav-
57 ing at one end a head carrying a bracket, and
58 a removable dome engaging the head, a lead
59 outlet pivotally connected with the head and
60 detachably connected with the bracket, the
61 major portion of said outlet being located
62 within the dome and a portion extending
63 through the dome, and means on said project-
64 ing portion for securing the dome in place
65 comprising a nut threaded upon said project-
66 ing portion and engaging exteriorly against
67 the dome.

68 5. In a generator including a housing hav-
69 ing at one end a head carrying a bracket, a
70 lead outlet comprising a curved arm pivoted
71 at one end to the head and having its other

72 end detachably connected with said bracket,
73 said arm being provided intermediate its
74 ends with an outstanding projecting portion
75 terminating in a tubular extension, said pro-
76 jecting portion being chambered and commu-
77 nicipating with the tubular extension and the
78 interior of the arm for the passage of the
79 leads.

80 6. In a generator including a housing hav-
81 ing at one end a head carrying a bracket, a
82 lead outlet comprising a curved arm pivoted
83 at one end to the head and having its other
84 end detachably connected with said bracket,
85 said arm being provided intermediate its
86 ends with an outstanding projecting portion
87 terminating in a tubular extension, said pro-
88 jecting portion being chambered and com-
89 municating with the tubular extension and the
90 interior of the arm for the passage of the
91 leads, a closure dome detachably engaged
92 with the head and apertured for engagement
93 upon the outstanding projection on the arm,
94 and means on said projection for clamping
95 the dome in place.

96 7. In a generator including a housing hav-
97 ing at one end a head carrying a bracket, a
98 lead outlet comprising a curved arm pivoted
99 at one end to the head and having its other
100 end detachably connected with said bracket,
101 said arm being provided intermediate its
102 ends with an outstanding projecting portion
103 terminating in a tubular extension, said pro-
104 jecting portion being chambered and commu-
105 nicipating with the tubular extension and the
106 interior of the arm for the passage of the
107 leads, a closure dome detachably engaged
108 with the head and apertured for engagement
109 upon the outstanding projection on the arm,
110 and means on said projection for clamping
111 the dome in place comprising a lever nut
112 threaded thereonto.

113 8. In a generator including a housing hav-
114 ing a head at one end, the combination of
115 a lead enclosing outlet pivotally connected
116 at one end with the head and having its other
117 end detachably mounted whereby the outlet
118 may be swung outwardly with respect to the
119 generator.

120 9. In a generator including a housing hav-
121 ing a head at one end, the combination of
122 a lead enclosing outlet pivotally connected at
123 one end with the head and having its other
124 end detachably mounted whereby the outlet
125 may be swung outwardly with respect to the
126 generator, closure means engageable with the
127 head, and means carried by said outlet for
128 securing said closure means in effective pos-
129 ition.

130 10. A generator comprising a housing, a
131 head at one end thereof, a bracket extending
132 from said head, a curved arm movably
133 mounted on said head and detachably con-
134 nected to said bracket, closure means adapted
135 to cover said bracket and arm, an extension
136 on said arm passing through said closure

means, and means threadedly engaging said extension for holding said closure means in place.

11. A generator comprising a housing, a head at one end thereof, a bracket extending from said head, a curved arm movably mounted with respect to said head at one end and detachably connected to said bracket at the other end, said arm being formed with a hollow extension serving as a lead outlet, said extension being provided with a threaded portion, a closure member apertured for receiving said extension and engaging the head around the periphery thereof, and a nut engaging the threaded portion of said extension for holding said closure member in place.

12. In construction of the character described, in combination, a generator having an open portion, a member pivoted thereto adjacent said open portion, said member and said generator being provided with means for detachably holding said member against swinging about its pivot, and a closure closing said open portion of the generator and for covering said member and its detachable connection, said closure being carried by said member.

13. In construction of the character described, in combination, a generator having an open portion, a member pivoted thereto adjacent said open portion, said member and said generator being provided with means for detachably holding said member against swinging about its pivot, a closure member adapted to close the open portion of said generator and to cover said member and its detachable connection, and means detachably connecting said closure to said member.

14. In construction of the character described, in combination, a generator having an open portion, means mounted adjacent said open portion and connected to said generator to be movable toward or away from said open portion, a closure adapted to close the open portion of said generator, and means securing said closure to said first-mentioned means.

15. In construction of the character described, in combination, a generator having an open portion, means mounted adjacent said open portion and connected to said generator to be movable toward or away from said open portion, a closure adapted to close the open portion of said generator, said first-mentioned means being provided with a passage adapted to guide the generator leads and said closure having an opening through which a portion of said means is adapted to pass, and means for securing said closure to said first-mentioned means.

16. In construction of the character described, in combination, a generator substantially open at one end, a closure member for closing the open end of said generator, means

within said closure member and having the latter secured thereto, and means mounting said first-mentioned means so that the latter is carried by said generator and connected to the latter to be movable at will toward or away from the open end of said generator.

In testimony whereof I affix my signature.

DONALD S. BARROWS.
